[57] **CLAIM**

The ornamental design for a torchiere lamp with a universal flex task light, as shown and described.

DESCRIPTION

FIG. 1 is a front elevational view of a torchiere lamp with a universal flex task light;

FIG. 2 is a right side view thereof;

FIG. 3 is a left side view thereof;

FIG. 4 is a top elevational view thereof;

FIG. 5 is a bottom view thereof; and,

FIG. 6 is a fragmentary side elevational view of a second embodiment of the design wherein the task light has a non-flexible center portion. The second embodiment is fragmentarily shown for convenience of illustration, it being understood that the second embodiment is identical to the first embodiment but for the non-flexible portion of the task light.
